UNITED STATES PATENT OFFICE.

ALFRED P. BARTLEY, OF OAKLAND, CALIFORNIA.

DESIGN FOR A RANGE.

36,492.

Specification for Design.

Patented Nov. 2, 1920.

Application filed August 3, 1920. Serial No. 401,085. Term of patent 14 years.

To all whom it may concern:

Be it known that I, ALFRED P. BARTLEY, a citizen of the United States, and a resident of the city of Oakland, county of Alameda, State of California, have invented a new, original, and ornamental Design for a Range, of which the following is a specification, reference being had to the accompanying drawings, forming part thereof.

One of the novel and dominant features

of my range is the positioning of the fire-box between the top gas-burners and the oven, the top of the oven being disposed in a higher plane than the top of the fire-box.

The figure is a perspective view of the range illustrating my new design.

I claim:

The ornamental design for a range, substantially as shown and described.

ALFRED P. BARTLEY.
